UNITED STATES PATENT OFFICE

140,515

DESIGN FOR A LAMP HOUSING FOR PICTURE PROJECTING APPARATUS OR THE LIKE

Otto R. Nemeth, Chicago, Ill., assignor to Products Development, Inc., Chicago, Ill., a corporation of Illinois

Application January 17, 1945, Serial No. 117,475

Term of patent 14 years

(Cl. D61—1)

To all whom it may concern:

Be it known that I, Otto R. Nemeth, a national of Czechoslovakia, residing at Chicago, in the county of Cook and State of Illinois, have invented a new, original, and ornamental Design for a Lamp Housing for Picture Projecting Apparatus or the like, of which the following is a specification, reference being had to the accompanying drawings, forming part thereof.

Figure 1 is a front elevational view of the lamp housing embodying my new design.

Fig. 2 is a top plan view of the lamp housing.
Fig. 3 is a side elevational view of the lamp housing.

The essential features of the design reside in the parts shown in full lines.

I claim:

The ornamental design for a lamp housing for picture projecting apparatus or the like, substantially as shown and described.

OTTO R. NEMETH.
